CLAIM

The ornamental design for a chair, as shown and described.

DESCRIPTION

FIG. 1 is a perspective view of a chair showing our new design;

FIG. 2 is a front elevational view thereof;

FIG. 3 is a left side elevational view thereof, the right side view being a mirror image of that shown; and,

FIG. 4 is a top plan view thereof.

The bottom and rear surfaces of the chair are not part of the design sought to be patented and are therefore not shown.
